COUNTERBALANCED GARAGE DOOR

Henry E. Skeels, Rochester, N. Y.

Application February 20, 1932, Serial No. 594,368

3 Claims. (Cl. 20—19)

The invention relates to a counterbalanced garage door.

The object of the present invention is to provide a simple, practical and efficient counterbalanced garage door of strong, durable and comparatively inexpensive construction, adapted to slide upwardly and inwardly or rearwardly in its opening movements and which will be perfectly counterbalanced both in its sliding and pivotal movements so that it may be easily operated manually with the slightest force to open or close.

A further object of the invention is to provide a counterbalanced means including a weight-receiving container and adapted without increasing the number of guide pulleys to enable the weight-receiving container to be arranged at either side of a garage and at either a front or rear corner thereof or at any other convenient point.

It is also an object of the invention to provide means for enabling the garage door to be shifted laterally slightly whereby to prevent any binding of the garage door against the door frame or other portion of the garage in the opening and closing movements of the garage door.

It is a further object of the invention to improve the means for attaching the flexible cables to the weight-receiving container and to provide a connection adapted to permit the said container to be adjusted vertically and also to permit a limited adjustment for leveling the container so that the container will set level or plumb in its vertical movements.

With these and other objects in view, the invention consists in the novel construction, combination and arrangement of parts hereinafter fully described, illustrated in the accompanying drawings, and pointed out in the claims hereto appended, it being understood that various changes in the form, proportion, and minor details of construction, within the scope of the claims, may be resorted to without departing from the spirit or sacrificing any of the advantages of the invention.

In the drawings:

Fig. 1 is an elevation of a counterbalanced garage door constructed in accordance with this invention, viewed from the inner face of the door and the latter being closed.

Fig. 2 is a diagrammatic view illustrating the arrangement of the counterbalancing means.

Fig. 3 is a vertical sectional view on the line 3—3 of Fig. 1.

Fig. 4 is an enlarged detail horizontal sectional view on the line 4—4 of Fig. 1.

Fig. 5 is a detail vertical sectional view of a portion of the weight-receiving container and the attached portions of the flexible cables.

Fig. 6 is a plan view of the weight-receiving container.

Fig. 7 is a vertical longitudinal sectional view showing the counterbalanced garage door open and illustrating another arrangement of the weight-receiving container.

Fig. 8 is a diagrammatic view of the counterbalancing means illustrated in Fig. 7.

In the accompanying drawings, in which is illustrated the preferred embodiment of the invention, 1 designates a single piece garage door, which may be of any desired construction and of any preferred dimensions and which is provided at opposite sides of its central portion with approximately U-shaped brackets 2 composed of spaced sides and a connecting portion secured to the inner face of the garage door by suitable fastening devices. The sides of the brackets 2 are provided with aligned openings 3 for the reception of shafts or spindles 4 and 5 to which flexible cables 6 and 7 are connected. The cables extend upward from the shafts 4 and 5 to overhead pulleys 8 and 9 and from the said pulleys to supplemental guide pulleys 10 and 11 which are located above a weight-receiving container 12 adapted to counterbalance the garage door.

The flexible cables or connections may be of any desired construction as will be readily understood and they are provided at their terminals 13 and 14 with suitable eyes receiving the shafts 4 and 5 and preferably formed by looping the said terminals of the cables. The shafts are provided with annular grooves 15 receiving the said eyes and adapted to prevent the same from sliding on the shafts 4 and 5 out of proper position. The shaft 4 has a threaded inner portion 16 receiving nuts 17 and 18 located at the opposite faces of the inner side of one of the U-shaped brackets 2 and adapted to adjust the garage door laterally, as hereinafter more fully explained, to prevent the same from binding against the door frame 19 in the opening and closing movements of the said garage door. The supplemental overhead guide pulleys 10 and 11 are located directly above the vertically movable weight-receiving container which may be placed at either side of the garage door at the front thereof and changing from one side to the other it merely requires a reversal of the arrangement of the pulleys shown in Fig. 2.

The flexible cables extend downwardly from the supplemental guide pulleys 10 and 11 to the

weight-receiving container 12 and their terminal portions 20 are overlapped and are passed beneath flanged attaching elements 21 and the terminal 22 of each of the flexible cables after extending 5 across the top of the weight-receiving container is secured to the other flexible cable by a clamp or clip 23. The clamp or clip 23 may be of any desired construction and the overlapped terminal portions 20 may be readily adjusted to shorten 10 the cables and also to permit a tilting adjustment of the weight-receiving container to arrange the same in a horizontal position so that it will set properly in its vertical movements.

The container is preferably oblong in plan view 15 as clearly shown in Fig. 6 of the drawings and the flanged members 21 preferably consist of a shank and an annular flange as clearly illustrated in Figs. 5 and 6 of the drawings. These flanged members are secured to a diagonally arranged 20 supporting member 24 extending across the top of the weight-receiving container from one corner to the diagonally opposite corner and having terminal portions 25 suitably secured to the end walls of the said container.

25 The horizontal shafts 4 and 5 extend laterally beyond the side edges of the door 1 and are provided at their outer ends with rollers 26 arranged to run in vertical channel guides 27 secured to the door frame 19 adjacent the door 30 opening as clearly illustrated in Figs. 1 and 4 of the drawings. The rollers 26 which are preferably ball bearing, as shown in Fig. 4, may be of any desired construction and the channel 35 guides 27 consist of channel bars provided at one of the side walls of its channel with a longitudinal flange 28 extending inwardly in parallelism with the web or body portions of the channel bars 27. This provides a groove 29 at one side of the guideway of the channel bar to receive the roller 40 26 and prevent lateral movement of the same so that by adjusting the nuts 17 and 18 the door may be shifted laterally with respect to the door frame so that the door will not bind in its opening and closing movements.

45 It is only necessary to provide the nuts 17 and 18 at one side of the garage door, as the shaft 5 at the other side of the door is loosely arranged 50 in the aligned openings of the supporting bracket 2. The roller 26 of the shaft 5 by being arranged in the groove 29 of the channel guide 27 will remain in proper position with respect to the channel guide in any lateral shifting of the garage door. The channel guides 27 which are vertical 55 are suitably secured to the door frame 19 and they extend downwardly from the top portion of the door frame to points below the horizontal shafts 4 and 5 when the door is in its closed position. This will afford ample movement for the main rollers 26 to carry the door 60 from the closed position shown in Fig. 1 to the open position illustrated in Fig. 7.

The door is provided with upper U-shaped brackets 30 constructed similar to brackets 2 and having aligned openings receiving upper shafts 65 31 upon which are mounted upper rollers 32 which operate in inclined channel guides 33 extending upwardly and rearwardly from the vertical channel guides and adapted when the garage door is lifted to cause the upper portion of the garage door to move inwardly or rearwardly 70 so that the garage door will occupy a horizontal position at the top of the garage when open.

The inclined channel guides 33 are suitably secured 75 at their lower ends to the vertical chan-

nel guides near the upper ends thereof and they are supported adjacent their upper rear ends by hanger bars 34 suitably secured to the frame of the garage at the top portion thereof and depending therefrom as clearly illustrated in Figs. 1 and 3 of the drawings. These hanger bars 34 are preferably angle iron bars but a hanger or bracket of any desired construction may be provided for supporting the inner or rear portions of the inclined channel guides 33. The inclined channel guides 33 are constructed the same as the vertical channel guides, being provided at the lower side of the channel or guideway with a longitudinal flange 35 to form a groove for holding the upper roller against lateral displacement. The garage door 1 is perfectly counterbalanced in both its sliding and pivotal movements and is adapted to be easily shifted manually by the exertion of only a very small amount of force to open and close the door and in the closing movement of the door, the inclined channel guides operate to retard the closing movement so that the door will close without slamming or banging.

In Figs. 7 and 8 of the drawings is illustrated another arrangement of the weight-receiving container which is located at the back of the garage at one corner thereof. The main overhead pulleys 36 and 37 are located at the front of the garage at opposite sides thereof and the supplemental guide pulleys 38 and 39 are located at the rear portion of the garage at one corner thereof. This will arrange the weight-receiving container in parallelism with the rear wall of the garage and while it is shown in Figs. 7 and 8 at one corner of the garage, it may be arranged at either corner or at the center thereof by changing the positions of the supplemental guide pulleys 38 and 39. In the arrangement illustrated diagrammatically in Fig. 8 of the drawings, the flexible connection 40 extends diagonally across the top of the garage from one front corner to the diagonally opposite rear corner and the other flexible connection 41 extends straight back from the overhead pulley 37 to the supplemental guide pulley 39. Simply shifting the positions of the guide pulleys will enable the weight-receiving container to be placed at either corner of the back of the garage or at the center thereof or at any intermediate point. The container is designed to be of a sufficient size to enable an ordinary garage door to be counterbalanced by sand or gravel placed in the container but with heavier doors, this weight may be supplemented with pieces of iron or other metal to secure the necessary weight for counterbalancing the doors. The garage door is a single piece or a single unit door; that is, the door 1 may be of any desired structure and consists of a single unitary structure to enable it to be perfectly counterbalanced both as to pivotal and sliding movements.

What is claimed is:

1. A pivotally and slidably counterbalanced garage door including vertical relatively short channel guides located at opposite sides of the upper portion only of the door opening of a garage, a single unit garage door, a pair of horizontally aligning U-shaped hangers secured at the central portions of the side edges of the door, shafts disposed horizontally in said hangers and extending beyond the sides of the door, rollers secured on the outer ends of said shafts and arranged in the vertical channel guides and movable upwardly and downwardly therein and cen-

trally pivoting the single unit door, the latter being counterbalanced on said rollers to permit free pivotal or swinging movement of the single unit door, means for counterbalancing the weight of the door in the upward and downward movement of the same, the shaft of one of said U-shaped hangers having screw threaded connection with such hanger so as to provide for a lateral adjustment of the door with respect to the door frame, and means for automatically tilting the single unit door when the same is moved upwardly and downwardly in said vertical channel guides, the latter means comprising relatively short upper inclined channel guides extending upwardly and rearwardly from the upper portions of the vertical channel guides and closed at their lower ends with respect to the vertical channel guides, and upper rollers carried by the single unit door and operating wholly within the upper inclined guides to effect the automatic tilting of the door when the same is raised and lowered.

2. A pivotally and slidably counterbalanced garage door including relatively short vertical channel guides located at the upper portion only of the door opening of a garage and on opposite sides of the door opening, a single unit garage door, a pair of hangers secured at the central portions of the side edges of the door, shafts mounted in said hangers and extending beyond the sides of the door, a roller carried at the outer end of each shaft and arranged in the vertical channel guides and movable upwardly and downwardly therein and centrally pivoting the single unit door, one of the shafts having a screw threaded connection with the hanger in which it is mounted whereby to provide for a lateral adjustment of the door with respect to the door frame and the door being perfectly counterbalanced on said central rollers to permit free pivotal

or swinging movement of the single unit door, means for counterbalancing the weight of the door in the upward and downward movement of the same, and means for automatically tilting the single unit door when the same is moved upwardly and downwardly in the vertical channel guides, the latter means comprising relatively short upper inclined channel guides extending upwardly and rearwardly from the upper portions of the vertical channel guides and closed at their lower ends with respect to the vertical channel guides, and upper rollers carried by the single unit door and operating wholly within the upper inclined guides to effect the automatic tilting of the door when the same is raised and lowered.

3. A pivotally and slidably counterbalanced garage door including vertical channel guides located at opposite sides of the door opening of a garage, a single unit garage door, a pair of brackets arranged in horizontal alignment and secured at the central portions of the sides of the door, horizontally aligning shafts mounted in said hangers, a roller secured at the outer end of each of said shafts and arranged in the vertical channel guides and movable upwardly and downwardly therein and centrally pivoting the single unit door, each of said shafts between the respective hangers and rollers having a groove therein, means for counterbalancing the weight of the door in the upward and downward movement of the same including cables having connection in the respective aforesaid groove of the aforesaid shafts, one of said shafts having adjustable connection with the respective hanger so as to provide for a lateral adjustment of the door with respect to the door frame, and means for automatically tilting the door when the same is moved upwardly and downwardly in the vertical channel guides, the latter means comprising relatively short upper inclined channel guides extending upwardly and rearwardly from the upper portions of the vertical channel guides and closed at their lower ends with respect to the vertical channel guides, and upper rollers carried by the door and operating within the upper inclined guides to effect the automatic tilting of the door when the same is raised and lowered.
